COMBINED FLOWER POT SUPPORT AND
FLOWER POTHoward E. Zerbe, P.O. Box 343, Kiwanis Trail, Du Bois, Pa.

Filed Sept. 10, 1962, Ser. No. 71,629

Term of patent 14 years

(Cl. D35—3)

Fig. 1.

Fig. 2.

Fig. 3.

Fig. 4.

FIG. 1 is a front perspective view of a combined flower pot support and flower pot showing my new design; and FIG. 2 is a rear perspective view thereof, and FIGS. 3 and 4 are top and bottom views, respectively. The broken line showing of a parking meter FIG. 1 is for purposes of illustration.

I claim:

The ornamental design for a combined flower pot support and flower pot, substantially as shown and described.
